ENGINE STARTER

Samuel Gilbert, Cedar Grove, N. J., assignor to
 Bendix Aviation Corporation, Teterboro, N. J.,
 a corporation of Delaware

Application September 18, 1947, Serial No. 774,718

2 Claims. (Cl. 123—179)

1

This invention relates to engine starters and particularly to novel means, in a starter adapted for direct cranking operation, for advancing an engine engaging member into engagement with the engine for starting the latter.

In a direct cranking starter, and in a combined direct cranking and inertia starter, the direct cranking feature involves an engine engaging member or jaw which is required to be restrained against rotation to effect its axial movement into engagement with the engine.

In many applications of comparatively wide, but moderate temperature varying range conditions, prior friction means, such as a split phosphor bronze ring, surrounding and biased against the jaw, has effected sufficient restraint.

However, with the field of operation of aircraft extended into colder regions, the simple friction means sometimes becomes ineffective, where fluid such as mixtures of oil, gasoline and other substances from the engine, enters and congeals, as between the threads of a screw shaft and a spline nut.

Such ineffectiveness is caused in part by the fact that the simple friction ring or means has a fixed value of friction or pressure, or a value that is intended to be fixed so far as its ability to retain the value is concerned.

With respect to the feature of congealing oil, as aforesaid, several suggestions have been advanced whereby a direct cranking starter jaw may be caused to engage the engine jaw under frigid conditions, such as a suggestion of means for positively holding the starter jaw until it engages the engine jaw and then releasing it for rotation to start the engine.

The latter suggestions involve structure which, although not complicated in consideration of the results obtained, are naturally not so simple as the former elemental friction means which fails under frigid conditions as stated.

An object of the present invention is to provide means which is substantially as simple as the fixed value friction means above noted, but which automatically varies the value of the frictional counterforce on the starter jaw to any value necessary to prevent rotation of the member.

Another object is to provide a wrap spring friction ring, providing for direct cranking starter jaw engagement with an engine, which is effective to give sufficient torque for cold starting when the screw shaft is subjected to engine oil.

Another object is to provide engine starter jaw advancing means which is simple and durable in

construction, economical to manufacture, and effective in its operation.

The above and other objects and features of the invention will appear more fully hereinafter from a consideration of the following description taken in connection with the accompanying drawing wherein one embodiment of the invention is illustrated by way of example.

In the drawing:

10 Figure 1 is a side view, generally in section having parts in elevation, of a portion of an engine starter embodying the invention; and

Figure 2 is a detail side section of a wrap spring seen in Figure 1.

15 Referring to Figure 1, a starter 10 comprises, in general, a baffle 12, an engine engaging member 14, associated with the baffle 12, and having an end jaw 16, a shank portion 18 of certain diameter disposed next to the jaw 16 and a shank portion 20 of smaller diameter behind the first shank portion 18 joined thereto by a ramp 22.

The member 14 is adapted to be restrained against rotation for axial movement of the jaw 16 into engagement with an engine jaw 24, and means provided for rotating the member 14 to effect such axial movement and to rotate the same to start the engine, as is further pointed out.

For combination with the above-mentioned elements, the invention comprises a resilient or flexible element, such as a flat strap 26 of phosphor bronze, see also Figure 2, connected adjacent to one end 28, as by an anchor rivet 30, to the baffle 12, and having a portion or convolutions 32 helically wound edgewise about the member 14 to a free end 34 of the strap 26 and responsive to rotative force on the member 14 for cooperation with the shank portion 18 to restrain the member 14 against rotation. The strap 26 and the shank portions 18 and 20 are related to the

40 jaw 16 such that, when the latter has reached its operative position for starting the engine, the strap 26 has axially ridden off the shank portion 18 and down the ramp 22 to free the member 14 from rotative restraint by the strap 26.

45 In further particular, the starter 10 comprises a housing portion 38 having a flange 40 for mounting the starter, as by studs 42, to an engine crank case 44, and a flange 46 for supporting a housing 48 of a motor 50 having a rotor 52 and a shaft 54. The latter is journaled, as by a bearing 56 in a partition 58, and carries a pinion or sun gear 60.

The baffle 12 comprises a member 62 to which 55 the strap 26 is riveted, and a member 64 secured

to the member 62 having a flange 66 between the flange 40 and the engine case 44.

The sun gear 60 meshes with planet gears 68, which mesh with an orbit gear 70 on the housing 38, and are mounted on a carrier 72 having a sun gear 74. The latter meshes with planet gears 76, which mesh with the orbit gear 70 and are carried by an end wall 78 of a barrel 80 rotatably mounted in the housing 38 and having a stub shaft 82 on which the sun gear 74 is journaled.

A torque limiting disc pack 84 has interlayered discs axially movably splined, but rotatively fixed, to the barrel 80 and to an axially stationary rotative nut 86, respectively, the friction between the discs being adjusted by springs 88, a ring nut 90 threaded in the barrel 80, and other elements in a usual manner.

A screw shaft 92, having long-lead thread relation to the nut 86, has an axially slid able spline connection 94 to the jaw member 14.

A mesh rod or member 96, held by a nut 98 in an opening in a central web portion of the member 14, compresses a sealing ring 99 against the web, and is provided with a flange 100 behind a flange 102 of the screw shaft 92. A spring 104 extends between the flange 100 and a backing ring 106 held to the shaft 92, as by a lock ring 108 in a groove in the shaft 92.

A seal ring 110, fixed to the baffle member 64, is maintained around the nut 86, as by a garter spring 112, in radially inwardly pressing sealing engagement with the nut.

In operation, with the parts in the inactive positions shown, corresponding to the retracted position of the jaw 16, the convolutions of the strap 26 engage the shank portion 18 to effect a predetermined degree of friction with this shank portion when the member 14 tends to rotate. This degree is such that, as in warm weather or when the parts are warm, for instance, the strap will operate substantially as an ordinary split friction ring, to restrain the member 14 from rotation, the jaw 16 then being moved forward into engagement with the engine jaw 24, because of the screw action of the screw shaft 92 within the spline nut 86.

However, where, as under cold conditions, above mentioned, the member 14 has a greater tendency to rotate with the screw shaft 92, caused as by being held sealed to the shaft by congealed oil, and requires greater force to break such seal, the strap 26, by reason of its wound relation to the shank portion 18, will wind more tightly on this shank portion. The tightness of this latter winding action will be substantially in accordance with the strength required to break the congealed oil, so that the wrap spring 26 will restrain the member 14 against turning or oppose the turning force with any one of several counterforces, dependent upon the torque required or the degree of congelation of the oil.

Although only one embodiment of the invention has been illustrated and described, various changes in the form and relative arrangements of the parts may be made to suit requirements.

What is claimed is:

1. In an engine starter comprising a baffle, an engine engaging member extending through said baffle having an end jaw, a shank portion of certain diameter disposed next to the jaw and a shank portion of smaller diameter behind the first shank portion joined thereby by a ramp, said member being adapted to be restrained against rotation for axial movement of the jaw into engagement with the engine, and means for rotating the member to effect said axial movement and to rotate the same to start the engine, the combination of a resilient flat strap connected adjacent to one end to said baffle and having a portion helically wound edgewise about the member to a free end of the strap and responsive to rotative force on the member for cooperation with said first shank portion to restrain the member against rotation, said strap and said shank portions being related to the jaw such that, when the latter has reached its operative position for starting the engine, the strap has axially ridden off said first shank portion and down said ramp to free the member from rotative restraint by the strap.

2. In an engine starter comprising a baffle, an engine member having a shank extending through said baffle, said shank having two shank portions, one of said portions being adapted to be restrained against rotation for axial movement of said member into engagement with the engine, and means for imposing rotative force on said member to effect said axial movement and rotate the same to start the engine, the combination of restraining means for said one shank portion connected adjacent one end of said restraining means to said baffle and having a portion wound about said one shank portion to a free end of said resilient means and responsive to said force for cooperation with said shank to restrain said member against rotation when in a disengaged position from said engine, and a second shank portion adjacent said first shank portion and including means for releasing said restraining action of said resilient means when said member is in engaged position with said engine.

SAMUEL GILBERT.
